UNITED STATES PATENT OFFICE

SAMUEL MARGHITAN, OF CHICAGO, ILLINOIS, ASSIGNOR TO MARQUETTE TOOL & MFG. COMPANY, OF CHICAGO, ILLINOIS, A CORPORATION OF ILLINOIS

DIE CUSHION

Application filed September 22, 1928. Serial No. 307,673.

This invention relates to die cushions, and its principal object is to provide cushioning means wherein the resistance to the pressure, afforded by the descending die, is not substantially increased as the die proceeds to the lower limit of its working stroke. There are many instances in die press work where it is desirable to maintain a substantially constant resistance to the moving die. For instance,

10 where the edge portion of the work is held between the moving die and a draw ring in performing certain drawing operations, it is highly desirable and sometimes necessary for the edges of the work to be held by a substantially constant pressure, and this invention

15 has been devised to meet this situation. The invention consists, therefore, in cushioning means for the dies of die presses, in which is embodied a spring or other yielding medium for exerting pressure in one direction against the dies, capable of bodily movement away from the work without substantially varying the effectiveness of the spring. It further consists in a cushioning means

20 having mechanism for holding it in opposition to the work at a substantially constant pressure, but permitting it to move bodily away from the work without substantially changing its effective resistance.

25 It further consists in the several novel features of construction, arrangement and combinations of parts hereinafter fully described and claimed.

The invention is clearly illustrated in the 30 accompanying drawings, in which—

Figure 1 is a view, partly in side elevation and partly in vertical section, of a die press partly broken away, and showing the same equipped with a die cushion embodying a

35 simple form of the present invention;

Fig. 2 is a detail horizontal section taken on the line 2—2 of Fig. 1;

Fig. 3 is a detail vertical section through the die cushion, showing the same upon an enlarged scale; and

Fig. 4 is a perspective view of a certain gear segment which forms part of the device.

Referring to said drawings, which illustrate one embodiment of the present invention, the reference character 10 designates

the bolster and 11 the frame of a die press of conventional form. Upon the bolster is secured the stationary die 12, and co-operating with said stationary die is the moving die 13 which is carried by the ram 14 as usual which is reciprocated by power operated actuating mechanism. Standards or posts 10^a extend up from the bolster and serve to guide the ram in its movements relative to the lower or stationary die.

55 In the form of die mechanism illustrated, a draw ring 15 is shown, against which the work, designated by *a*, is held in frictional engagement by the upper die 13 during its down or working stroke. As usual, the draw ring is supported on draw ring pins 16 which extend through and are guided in the bolster. Said draw ring pins move with the draw ring and rest upon the die cushion 17 which forms the subject matter of this invention, and will now be described in detail.

60 In the form of the invention illustrated, a gear housing 18 is provided which, as shown, has a top plate 19 upon which the draw ring pins 16 stand, and transmit the pressure from the moving die to the die cushion. Said gear housing 18 is mounted to move in alignment with the direction of movement of the upper die, and is here shown as provided with a stem or sleeve 20 on its lower side which is 65 slidably mounted on a fixed, or stationary, sleeve 21 supported by the bolster of the press. Conveniently the stem or sleeve 20 may have a threaded connection with the gear housing 18, as shown at 22. The stationary sleeve 21 is supportingly connected to the bolster by a tie rod 23 which extends up through the sleeve 21 and is secured in the bolster by a threaded connection as at 24. On the lower end of the tie rod is a nut 25 and washer 26, the latter of which bears against the lower end of the stationary sleeve 21 and secures it against endwise movement.

70 Between the stationary sleeve 21 and top plate 19 of the gear housing 18 is a stationary rack bar 27 which has rack teeth 28 on two or more of its faces, and between the rack bar 27 and bolster is a stationary sleeve 29 which abuts against the lower face of the bolster. The stationary sleeve 21 and 29 and the rack

bar 27 are tied or secured to the bolster against endwise movement by the tie rod 23, nut 25 and washer 26. The stationary sleeves 21 and 29 and rack bar 27 may be formed in one piece or several as desired.

Connected to the gear housing 18 by connecting mechanism, hereinafter described, is a link supporting collar or bearing member 30 which surrounds the stem or sleeve 20 and is movable lengthwise thereon, and bearing against the lower side of said collar 30 is a coiled compression spring 31, or other yielding cushioning member, which serves to yieldingly resist the downward movement of the gear housing and parts directly supported thereby. The coiled compression spring 31 is confined between the lower side of the collar 30 and a nut 32 and interposed washer 33 adjustably held on the threaded lower end 20 of the stem 20. It is to be understood that the action of the compression spring 31 is transmitted from the lower end of the stem 20 to the top plate 19 of the gear housing 18 through the collar 30 and certain connecting members, which will now be described.

Meshing with the rack teeth of the rack bar 27 are gear segments 34, the teeth of which are formed on the circumferences of disks 35 (see Fig. 4) and project laterally from one of the faces thereof, as is clearly shown in said figure. Each disk has a hub portion 36 through which extends a journal pin or short shaft 37 which is mounted in side plates or frame members 38 that project down from the top plate 19 of the gear housing and connect with the stem 20 through the threaded connection at 22. The pins or shafts 37 are disposed in a line running at right angles to the axes of the sleeves and tie rod, and the radii of the gear segments are of equal length.

The hub portions 36 are in the form of eccentric blocks, and upon said eccentric blocks are mounted the upper ends 39 of links 40, the lower ends of which are connected to the collar 30 by pins 41. The upper ends of the links 40 are contained in the space between the side faces of the disks 35 and inner faces of the side plates 38 (see Fig. 2). With the eccentric blocks 36 located with respect to the gear segments, as shown in the drawings, the major axes thereof become disposed horizontally when the gear housing has been moved downwards a distance approximately equal to one half of its stroke. This location of the eccentric blocks is not essential to the invention broadly considered as it may be varied as desired.

In the operation of the die cushion, and with the gear housing moved up against the bolster 10, the compression spring 31 presses upward on the collar 30, which transmits the upward pressure to the gear housing 18 through the links 40, eccentric blocks 36 and pins 37. Because of the intermeshing rack

bar and gear segments, the major axes of the eccentric blocks have been rotated around the axes of the pins 37 from the position seen in full lines in Fig. 3 to one approximating the vertical, or at least approximately forty-five degrees to the horizontal.

If now a sheet of metal is placed between the two dies, and the upper die is brought down upon the work, it will first clamp its edge portion upon the draw ring and then move the work down, in drawing it, at the same time forcing down the draw ring 15 and therewith the draw ring pins 16, the latter forcing down the gear housing 18 a distance corresponding to the distance traveled by the draw ring pins. The downward pressure on the gear housing is transmitted to the pins 16 and thence to the eccentric blocks 36 and from them to the links 40, which in turn transmit the pressure to the collar 30 and thence to the compression spring 31, which transmits it to the collar 33 on the stem 20 of the gear housing. However, inasmuch as the gear segments are bodily moved down with the gear housing, they roll down the rack bar and turn the eccentric blocks on the axes of the gear segments, thereby moving down the links relative to the gear housing and compressing the spring 31 slightly. When the pressure is removed from the top of the gear housing, the spring 31 forces the collar and links upward, thereby turning the gear segments back and, consequently, lifting the gear housing up against the bolster.

I claim as new, and desire to secure by Letters Patent:

1. In a die cushion, the combination of a rack bar fixed against endwise movement, a gear housing movable lengthwise of said rack bar, a gear segment meshing with said rack bar and rotatably mounted on said gear housing, an eccentric block eccentrically disposed on said gear segment, a link mounted upon said eccentric block, and resilient means held under compression between said gear housing and link.

2. In a die cushion, the combination of a rack bar, fixed against endwise movement, a gear housing movable lengthwise of said rack bar, gear segments meshing with said rack bar and rotatably mounted in said gear housing, eccentric blocks, one disposed on each gear segment, links, one mounted upon each eccentric block, and resilient means held under compression between said gear housing and links.

3. In a die cushion, the combination of a rack bar, fixed against endwise movement, a gear housing movable lengthwise of said rack bar, gear segments meshing with said rack bar and rotatably mounted in said gear housing, eccentric blocks, one eccentrically disposed around the axis of each gear segment, links, one mounted on each eccentric block, a link supporting collar, and a coiled

compression spring held under compression between said link supporting collar and a member connected to said gear housing.

4. In a die cushion, the combination of a rack bar arranged to be secured to the bolster of a die press, a gear housing movable lengthwise of said rack bar and having a downwardly projecting stem, gear segments meshing with said rack bar and rotatably mounted in said gear housing, eccentric blocks, one eccentrically disposed around the axis of each gear segment, links, one mounted on each eccentric block, a link supporting collar surrounding said stem and connected to said links, and a coiled compression spring held under compression between said link supporting collar and a shoulder on said stem.

5. In a die cushion, the combination of a rack bar arranged to be secured to the bolster of a die press, a gear housing movable lengthwise of said rack bar, gear segments meshing with said rack bar and rotatably mounted on said gear housing, eccentric blocks, one disposed eccentrically around the axis of each gear segment, links, one mounted on each eccentric block, a link supporting collar connected to said links, and a coiled compression spring held under compression between said link supporting collar and an extension of said gear housing.

6. In a die cushion, the combination of a rack bar, a sleeved member extending down therefrom, a tie rod extending through said sleeve and rack bar and supporting the same on a die press bolster, a gear housing movable lengthwise of said rack bar and having a downwardly projecting stem surrounding said sleeve, gear segments meshing with said rack bar and rotatably mounted in said gear housing, eccentric blocks, one eccentrically disposed around the axis of each gear segment, links, one mounted on each eccentric block, a link supporting collar surrounding said stem and connected to said links, and a coiled compression spring held under compression between said link supporting collar and a shoulder on said stem.

7. In a die cushion, the combination of a rack bar, a sleeved member extending down therefrom, a tie rod extending through said sleeve and rack bar and supporting the same on a die press bolster, a gear housing movable lengthwise of said rack bar and having a downwardly projecting stem surrounding said sleeve, gear segments meshing with said rack bar and rotatably mounted in said gear housing, eccentric blocks, one eccentrically disposed around the axis of each gear segment, links, one mounted on each eccentric block, a link supporting collar surrounding said stem and connected to said links, a collar adjustably secured on said stem, and a coiled compression spring held under compression between said collars.

8. In a die cushion, a stationary member,

spaced movable members, resilient means interposed between the stationary member and the movable members for yieldingly resisting the movement of the latter, a cam device supported by one of the movable members for movement therewith and with respect thereto, a link connection between said cam device and the other of said movable members, teeth on the cam device, and a stationary rack with which the teeth engage whereby the cam will be shifted with respect to its support for influencing the said resilient means through the said links and during the movement of the cam with its support.

9. In a die cushion, a stationary member, spaced movable members, resilient means interposed between the stationary member and the movable members for yieldingly resisting the movement of the latter, an eccentrically mounted cam device supported by one of the movable members for movement therewith and with respect thereto, a link connection between said cam device and the other of the said movable members, and means for rotating the cam device with respect to its support during the movement of the cam with its support, for influencing the said resilient means through the said links.
